UNITED STATES PATENT OFFICE.

GEORGE H. HOLLAND, OF ST. LOUIS, MISSOURI, ASSIGNOR TO THE BRIDGE & BEACH MANUFACTURING COMPANY, OF SAME PLACE.

DESIGN FOR A COOKING-STOVE.

SPECIFICATION forming part of Design No. 21,806, dated August 30, 1892.

Application filed July 30, 1892. Serial No. 441,771. Term of patent 14 years.

To all whom it may concern:

Be it known that I, GEORGE H. HOLLAND, a citizen of the United States, residing in the city of St. Louis, State of Missouri, have invented and produced a new and original Design for Cooking-Stoves, of which the following is a specification, reference being had to the accompanying drawing, forming a part thereof.

10 The drawing represents a perspective view of the stove, taken from a point of view somewhat above the level of the top of the stove and a short distance in front and to the right-hand side of the stove, taking the front to be 15 that end of the stove from which the ash-pit projects.

The leading features of my design in the stove as a whole are the following: The coal-chute extends from the upper part of the 20 front of the stove, the door of which extends in an inclined curve from the front edge of the top casting. In the chute-door are formed the check-draft openings. From the lower edge of the chute-door the bottom of the chute 25 extends in an inclined direction until it meets the front plate of the stove. From immediately below the conjunction the chute-bottom and the front plate of the stove is the upper edge of the front pillar-door, which is formed 30 with curved upper and end edges and the door as a whole curved in its length across the front of the stove. The upper portion of the front fire-box door is stippled and the lower portion provided with the draft-openings. The hearth- 35 plate extends from the lower edge of the front fire-box door in a forward direction on a level corresponding approximately one-third of the height of the body of the stove above the bottom of the oven. The edges of the hearth- 40 plate are curved downwardly similar to the top casting. The side edges of the hearth-plate extend back beyond the front side of the stove until they meet the front edge of the oven-door. Between the backwardly-projecting edges of the hearth-plate and the lower edge of the side fire-box door and between the front edge of the stove and the front edge of the oven-door. Beneath the hearth-plate is 45 the ash-pit, which extends in depth to approximately the level of the bottom of the oven. The side fire-box door is formed with an inclined rear edge and is ornamented with a

branch of a grape-vine with attached bunch of grapes and leaves. The bottom plate of the stove projects all around beyond the side 55 and end plates of the stove in a convex-curved edge corresponding to the edges of the top casting and hearth-plate. The oven-door is formed with straight edges at the top and bottom and back, the lower edge being longer 60 than the upper, the upper forward corner being cut away to allow for the fire-box. The front edge of the door is vertical to where it is cut away immediately under the rear side of the side fire-box door, leaving a space between it and the front edge of the side plate of the stove exposed, which is ornamented with a bunch of grape-leaves. The oven-door is ornamented with a branch of a grape-vine extending diagonally across the same 70 from the lower front corner to the upper rear corner. To the branch is attached leaves and bunches of grapes, and there is perched thereon a bird in the act of picking at one of the bunches of grapes. In approximately the 75 center of the door is a medallion-plate, in the center of which is the representation of a bunch of grapes in relief. The door as a whole is formed with rounded curved edges, except at the bottom edge, making the door 80 convex on the exterior. Extending along the side of the stove, of about the length of the oven-door, is the extension oven-bottom shelf, on which is placed in relief a scroll of grape-leaves on a stippled or roughened back- 85 ground.

The stove as a whole is mounted on the base, which from where it joins the bottom plate curves outwardly in approximately a quadrant of a circle. The lower edge is formed 90 with a double raised head which extends at the corners up to the upper margin of the base and then turns on itself, terminating in a number of radial sprays. The base as a whole is ornamented with two branches of a 95 grape-vine, the stock ends of which are crossed at the middle of the length of one side, surmounted with a bunch of grapes extending toward either end, provided with leaves, all in raised work. The base rests on the four 100 feet, which are arranged on the diagonals from corner to corner, curved outwardly at the bottom, and tapering in a gentle curve from the comparatively wide tops to the lower

extremity. The general shape of the exterior surface, as looked at diagonally across one of the corners, is a compound curve, the upper member of which corresponds to the curve given to the cross-sectian of the base.

5 I claim—

The design for a cooking-stove, substantially as shown and described.

In testimony whereof I hereto affix my signature, in the presence of two witnesses, this 26th 10
day of May, 1892.
